(57) **CLAIM**

The ornamental design for a chiller, as shown and described.

DESCRIPTION

FIG. 1 is a front, right, top perspective view of a chiller; FIG. 2 is a rear, left, bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of a portion 9 of FIG. 2; and, FIG. 10 is an enlarged view of portion 10 of FIG. 2. The broken lines in the drawings depict portions of the chiller that form no part of the claimed design.
